(57) **CLAIM**

The ornamental design for a double pulling stick tool for
repairing auto body panels, as shown and described.

DESCRIPTION

FIG. 1 is an exploded view of a double pulling stick tool for
repairing auto body panels, showing my new design;

FIG. 2 is a perspective view of the double pulling stick tool for
repairing auto body panels in the assembled full length configura-
tion;

FIG. 3 is a perspective view of the tool of FIG. 1, in a
shortened configuration;

FIG. 4 is a top plan view of FIG. 2;

FIG. 5 is a front view of FIG. 2;

FIG. 6 is a bottom view of FIG. 2;

FIG. 7 is a top plan view of FIG. 3;

FIG. 8 is a front view of FIG. 3;

FIG. 9 is a bottom plan view of FIG. 3;

FIG. 10 is a right side view of the tool in both the full length
and shortened configurations; and,

FIG. 11 is a left side view of the tool in either a long or short
configuration.
